SAFETY HELMET

De Anna M. Breece, El Monte, Calif.,
(1336 Galway, Billings, Mont. 59101)

Filed Sept. 9, 1974, Ser. No. 504,037

Term of patent 14 years

Int. Cl. D2—03

U.S. Cl. D2—232

FIG. 1 is a perspective view of a safety helmet, showing my new design;

FIG. 2 is a view thereof taken in the direction of arrow 2 in FIG. 1;

FIG. 3 is a view thereof taken in the direction of arrow 3 in FIG. 1;

FIG. 4 is a bottom view thereof.

I claim:

The ornamental design for a safety helmet, as shown and described.
